COMBINED GARBAGE CAN AND SUPPORT THEREFOR

Arthur U. Griggers, 351 Hickory St.,
Greenville, Ala. 36037

Filed Dec. 4, 1969, Ser. No. 20,358

Term of patent 14 years

Int. Cl. D7—06

U.S. Cl. D49—35

FIG. 1 is a side elevational view of a combined garbage can and support therefor showing our new design, the side not shown being identical to the side shown; and,

FIG. 2 is a top plan view thereof.

We claim:

The ornamental design for a combined garbage can and support therefor, as shown and described.
